(57) **CLAIM**

The ornamental design for a battery case for portable radio, as shown and described.

DESCRIPTION

FIG. 1 is a top, side and end perspective view of my design for a battery case for portable radio;

FIG. 2 is a plan view thereof;

FIG. 3 is a bottom view thereof;

FIG. 4 is an elevation view thereof from the side shown in FIG. 1;

FIG. 5 is an elevation view thereof from the side opposite that in FIG. 4;

FIG. 6 is an elevation view thereof from the end shown in FIG. 1; and,

FIG. 7 is an elevation view thereof from the end opposite that in FIG. 6.

The portion of the battery case for portable radio shown in dotted lines does not constitute a part of the claimed design. The designations "plan", "bottom", "side" and "end" are arbitrary since the device is intended to be situated and usable in virtually any orientation.
